SHEAR SHARPENER

Charles B. Mozdy, San Diego, Calif.

Application July 22, 1940, Serial No. 346,849

2 Claims. (Cl. 51—157)

My invention relates to a shear sharpener, more particularly for use in sharpening barber's shears or the like, and the objects of my invention are:

First, to provide a shear sharpener of this class which is arranged to sharpen shears at various angles on the blades from the cutting edges thereof;

Second, to provide a shear sharpener of this class in which a flat, smooth, hard surfaced abrasive sheet supporting plate is arranged to support various grades of abrasive sheet material thereon for providing a number of different abraded corrugations in the sharpened shear cutting edges sharpened by my shear sharpener;

Third, to provide a shear sharpener of this class which is particularly adapted for use in sharpening barber's shears due to the abrasive sheet used thereon, which provides sharp, well defined corrugated cutting portions on the edges thereof which reduce slippage of the hair relatively therewith to a minimum when cutting the same;

Fourth, to provide a shear sharpener of this class in which a guide rod is reciprocally mounted in a universally operative guide rod supporting sleeve for convenient manipulation of the shear sharpener and shears in connection therewith when sharpening the same;

Fifth, to provide a novel shear sharpener of this class;

Sixth, to provide a shear sharpener of this class in which a tapered angle adjusting member is readily reversible or removable for changing the sharpening angle of the shears being sharpened by my shear sharpener;

Seventh, to provide a shear sharpener of this class in which the angle adjusting member provides definite desired angle setting for repeating individual shear blade sharpening; and

Eighth, to provide a shear sharpener of this class which is very simple and economical of construction, accurate and efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application in which:

Figure 1 is a longitudinal sectional view of my

shear sharpener taken from the line 4—4 of Fig. 2 showing parts and portions in elevation to facilitate the illustration and also showing portions of a pair of shears in connection therewith; Fig. 2 is a transverse sectional view taken from the line 2—2 of Fig. 1 showing parts and portions in elevation to facilitate the illustration and also showing portions of a pair of shears in connection with my shear sharpener; Fig. 3 is a transverse sectional view taken from the line 3—3 of Fig. 1 showing parts and portions in elevation to facilitate the illustration and Fig. 4 is a fragmentary sectional view taken from the line 4—4 of Fig. 1.

Similar characters of reference refer to similar parts and portions throughout the several views of the drawing:

The abrasive sheet supporting plate 1, abrasive sheet 2, abrasive sheet clamping members 3 and 4, shear blade clamping members 5 and 6, guide rod 7, guide rod supporting sleeve member 8, sleeve supporting member 9, bolt 10, spacer member 11, angle adjusting member 12 and the bolts 13 and 14 constitute the principal parts and portions of my shear sharpener.

The abrasive sheet supporting plate 1 is a flat, smooth hard surfaced rectangularly shaped member and is preferably made of plate glass which provides a straight even hard surface upon which is positioned the abrasive sheet 2.

The abrasive sheet 2 is provided with an abrasive surface which is positioned outwardly from the abrasive sheet supporting plate 1 and the opposite ends of the abrasive sheet 2 are folded over opposite ends of the abrasive sheet supporting plate 1, as shown best in Fig. 1 of the drawing.

The abrasive sheet clamping members 3 and 4 are substantially U-shaped in cross section and these clamping members 3 and 4 are resilient and are arranged to clamp the abrasive sheet 2 over the opposite ends of the abrasive sheet supporting plate 1 in the relation, as shown best in Fig. 1 of the drawing. It will be noted that the abrasive sheet 2 is provided with an abrasive surface 2a, which surface 2a may be composed of relatively coarse or fine abrasive material as desired. Several separate abrasive sheets may be alternately arranged in connection with the abrasive sheet supporting plate 1 to provide several different coarse or fine corrugated sharpened surfaces on different shear blade cutting edges.

The shear blade clamping members 5 and 6 are arranged to clamp the conventional shear

blade in the relation as shown in Figs. 1 and 2 of the drawing whereby the cutting edge of the shear blade is held in a certain fixed angular relation with the abrasive surface 2a of the abrasive sheet 2, as shown best in Fig. 1 of the drawing. The back angular edge of the shear blade B is held in position by pins 5b extending inwardly from the clamping member 5. Secured to the shear blade clamping member 5 is a bolt 14 which is arranged to extend through the shear blade clamping member 6 and is provided with a screw threaded portion extending outwardly from the shear blade clamping member 6 and this screw threaded portion of the bolt 14 is engaged by the nut 14a, as shown best in Fig. 1 of the drawing. This nut 14a in its screw threaded relation with the bolt 14 provides means whereby the shear blade clamping members 5 and 6 may be manually forced together for securely holding the shear blade therebetween, as shown best in Fig. 1 of the drawing. Positioned intermediate the shear blade clamping members 5 and 6 on the bolt 14 is a spring 14b which is arranged to force the shear blade clamping members 5 and 6 into open position when released by the nut 14a for removing the shear blade from the shear blade clamping members 5 and 6.

The shear blade clamping member 5 is provided with an angularly extending portion at its upper end in which is fixed a bolt 13. This bolt 13 extends upwardly through the angle adjusting member 12 and the flattened end portion 7a of the guide rod 7, as shown best in Figs. 1 and 2 of the drawing. Positioned on the bolt 13 adjacent the upper side of the flattened portion 7a of the guide rod 7 is a resilient washer member 13a in engagement with the upper side of which is a washer 13b against which is positioned a nut 13c screw threaded on the upper end of the bolt 13. This nut 13c is provided with openings 13d in the side walls thereof arranged to receive a conventional cotter pin 13e which extends through the bolt 13, as shown best in Figs. 1 and 2 of the drawing. Positioned in the portion 7a of the guide rod 7 and extending downwardly therefrom is a pin 7b. This pin 7b is arranged to engage the angular portions 5b of the shear blade clamping member 5 when pivoted to a certain degree relatively with the guide rod 7.

The angle adjusting member 12 is positioned on the bolt 13 intermediate the portion 7a of the guide rod 7 and the angularly extending portion 5a of the shear blade clamping member 5, as shown best in Figs. 1 and 2 of the drawing. This angle adjusting member 12 is provided with upwardly extending side edge portions 12a which are arranged to embrace opposite side edges of the portion 7a of the guide rod 7, as shown best in Fig. 2 of the drawing. It will be noted that this angle adjusting member 12 is tapered and that opposite ends thereof are interchangeable in position providing a definite fixed variety of angles of the shear blade clamping member 5 relatively with the guide rod 7. It will be further noted that this angle adjusting member 12 may be entirely removed from the bolt 13 in its relation with the guide rod 7 and the shear blade clamping member 5, providing another angle of the shear blade clamping member 5 relatively with the guide rod 7.

The guide rod 7 is substantially circular in cross section, as shown in Fig. 3 of the drawing, and is reciprocally mounted in the guide rod supporting sleeve member 8, as shown best in Fig. 1 of the drawing.

The guide rod supporting sleeve member 8 is pivotally mounted on the sleeve supporting member 9 by means of the outwardly extending trunnions 8a which are positioned in holes 9a of the sleeve supporting member 9, as shown best in Fig. 3 of the drawing. The trunnions 8a are preferably integral with the guide rod supporting sleeve member 8.

The sleeve supporting member 9 is provided with an internally screw threaded portion arranged to engage the screw threaded portion 10a of the bolt 10, as shown best in Fig. 3 of the drawing. The guide rod 7, in engagement with the internal bore 8b of the guide rod supporting sleeve member 8 may be shifted relatively with the bolt 10 into various positions corresponding to movements promoted by a universal joint. The sleeve supporting member 9 in its revoluble screw threaded relation with the bolt 10 and the pivotally mounted guide rod supporting sleeve member 8, provide for relatively universal movements and shifted relation of the guide rod 7 relatively with the bolt 10 which is rigidly connected with the abrasive sheet clamping member 4 by means of welding, brazing or otherwise.

The spacer member 11 is positioned on the bolt 10 intermediate the abrasive sheet clamping member 4 and the lower side of the sleeve supporting member 9, as shown best in Fig. 1 of the drawing, providing proper elevated position of the guide rod supporting sleeve member 8 for accurately supporting the guide rod 7 in its relation with the cutting angle of the abrasive surface 2a of the abrasive sheet 2 in its relation with the shear blade held by the shear blade clamping members 5 and 6.

The operation of my shear sharpener is substantially as follows: When it is desired to sharpen shears A with my shear sharpener, the two opposing shear blades B and C are alternately clamped between the shear blade clamping members 5 and 6, as shown best in Figs. 1 and 2 of the drawing. When the shears A are clamped between the shear blade clamping members 5 and 6, as shown best in Fig. 1 of the drawing, the cutting edge of the shear blade B is moved backwardly and forwardly upon the abrasive surface 2a of the abrasive sheet 2. The shear blade C, disposed in substantially vertical position, as shown best in Fig. 2 of the drawing is arranged in close relation with the side edge of the shear blade clamping member 5 so that the entire length of the cutting edge of the horizontally disposed shear blade B may be sharpened. It will be noted that the shear blade clamping members 5 and 6 may be adjusted in any angular relation with the guide rod 7, by means of the bolt 13 in its pivotal relation with the guide rod 7.

By magnifying the cutting edge of a shear blade which has been sharpened upon my shear sharpener, it is easy to see the fine corrugated abrasions in the metal of the cutting edge. These fine corrugations, as hereinbefore described, are very useful in providing frictional engagement with the hair being cut by the shears so that the hair does not have a tendency to slip forwardly between the closing shear blades. As hereinbefore stated, abrasive sheets of varying abrasive coarseness or fineness may be employed. The particular abrasive papers I have found best suited for shear sharpening in connection with my shear sharpener are the abrasive paper sheets numbers 400, 320 and 220. Other grades of abrasives may be

used as desired for sharpening shears and other instruments. The use of this particular type of abrasive provides an abrasive surface which is adjustable in its coarseness or fineness and which may be renewed as desired for the formation of sharp and well defined corrugations in the cutting edge of the shear blade. The shear blade clamping members 5 and 6 are adjustable relatively with each other by means of the nut 14a in its screw threaded relation upon the bolt 14 which is secured to the shear blade clamping member 5. By tightening or loosening the nut 14a, the shear blade may be secured between the shear blade clamping members 5 and 6 or released therefrom. When the shear blade, in connection with the clamping members 5 and 6, is shifted backwardly and forwardly over the abrasive surface 2a, the guide rod 7 reciprocates in the guide rod supporting sleeve member 8 and holds the clamping members 5 and 6 together with the shear blade in proper angular relation with the abrasive surface 2a. If it is desired to sharpen the cutting edges of different shears at different angles, the angle adjusting member 12 may be reversed in its relation with the guide rod 7 on the bolt 13 so that the tapered portions thereof intermediate the portion 7a of the guide rod 7 and the angularly extending portion 5a of the shear blade clamping member 5 provides varying fixed angular relation of the clamping member 5 with the guide rod 7.

It will be noted that the angle adjusting member 12 may be removed so that the surface of the angularly extending portion 5a is in engagement with the portion 7a of the guide rod 7. This arrangement provides still another angular relation of the shear blade clamping member 5 relatively with the guide rod 7.

When it is desired to change or replace the abrasive sheet 2, the abrasive sheet clamping members 3 and 4 are forced off the ends of the abrasive sheet supporting plate 1 and a fresh abrasive sheet 2 is placed over one side of the abrasive sheet supporting plate 1 and the opposite ends of the abrasive sheet 2 are folded over the opposite ends of the abrasive sheet supporting plate 1. The abrasive sheet clamping mem-

bers 3 and 4 are then forced over the abrasive sheet 2 at opposite ends of the abrasive sheet supporting plate 1, as shown best in Fig. 1 of the drawing.

Though I have shown and described a particular construction, combination and arrangement of parts and portions, I do not wish to be limited to this particular construction, combination and arrangement, but desire to include in the scope of my invention, the construction, combination and arrangement substantially as set forth in the appended claims.

Having thus described my invention, what I claim as new and desire to secure by Letters Patent is:

1. In a shear sharpener of the class described, the combination of reciprocally mounted shear blade clamping means, a guide rod connected therewith, a reversibly mounted wedge-like tapered angle adjusting member positioned intermediate said guide rod and said shear blade clamping means arranged for adjusting the angle of the shear for providing a proper bevel on the shear blade, and universally operative means in supporting relation with said guide rod, said shear blade clamping means pivotally connected with said guide rod whereby the angle of the shear blade clamping means may be varied in relation with said guide rod.
2. In a shear sharpener of the class described, the combination of reciprocally mounted shear blade clamping means, a guide rod connected therewith, a reversibly mounted wedge-like tapered angle adjusting member positioned intermediate said guide rod and said shear blade clamping means arranged for adjusting the angle of the shear for providing a proper bevel on the shear blade, universally operative means in supporting relation with said guide rod, said universally operative means including a pivotally mounted guide rod supporting sleeve member and a revolvably mounted sleeve supporting member, said guide rod supporting sleeve member pivotally connected with said sleeve supporting member at right angles to the revolvably mounted axis thereof.

CHARLES B. MOZDY.
